UNITED STATES PATENT OFFICE.

JOHN E. GENN, OF CHICAGO, ILLINOIS, ASSIGNOR TO STEWART-WARNER SPEEDOMETER CORPORATION, OF CHICAGO, ILLINOIS, A CORPORATION OF VIRGINIA.

PORTABLE SIGNAL DEVICE.

1,344,082.

Specification of Letters Patent. Patented June 22, 1920.

Application filed December 13, 1918. Serial No. 266,527.

To all whom it may concern:

Be it known that I, JOHN E. GENN, a citizen of the United States, residing at Chicago, in the county of Cook and State of Illinois, have invented certain new and useful Improvements in Portable Signal Devices, of which the following is a specification, reference being had to the accompanying drawings, forming a part thereof.

The purpose of this invention is to provide a portable signal device of the type employing a forcibly vibrated diaphragm designed for heavy duty, especially on outdoor work and adapted to be readily moved about and set up temporarily at any desired location. It is thus fitted for use as a signal on building operations, as a warning signal in mines or quarries where blasting is done, or in warfare as an alarm in the event of a gas attack. The invention comprises various features and elements of the structure hereinafter described and shown in the drawings as indicated by the claims.

In the drawings:

Figure 1 is a vertical sectional view, section being taken substantially in a plane parallel to one of the diaphragms and showing the interior construction of the device including the driving train for the tooth wheel which vibrates the diaphragm.

Fig. 2 is a section taken transversely with respect to Fig. 1 at a plane indicated at line 2-2 on Fig. 1 and indicating the mode of engagement of the toothed cam wheel with the contact buttons of the two diaphragms.

Fig. 3 is a top plan view of one form of signal fitted with two horns for discharging the sound from both diaphragms in the same direction.

Fig. 4 is a top plan view similar to Fig. 3, but showing a modification in which the horns discharge in opposite directions.

Fig. 5 is a detail elevation partly in section showing a swivel mounting bracket for securing the signal to a vertical surface.

Fig. 6 is an elevation partly in section showing a modified mounting device in the form of a post or stake to which the casing of the alarm is swivelly attached at the top.

Fig. 7 is a detail section showing a further modification of the mounting means consisting in a heavy wood screw secured directly to the casing of the alarm device.

From Figs. 1 and 2 it will be seen that the signal device consists briefly of a casing,

1, preferably provided with two substantially parallel diaphragms or drum heads, 2 and 3, inclosing a toothed wheel, 4, journaled for rotation between the two diaphragms, 2 and 3, with its corrugated periphery simultaneously in contact with the contact buttons, 5 and 6, of said diaphragms respectively. The wheel, 4, is rigidly carried on a shaft, 7, provided with a pinion, 8, which meshes with a drive gear, 9, on a shaft, 10, fitted outside the casing, 1, with a driving crank, 11. The corrugated periphery, 12, of the toothed wheel, 4, has the form of a truncated cone, so that its teeth stand in a slightly oblique relation to the planes of the diaphragms, 2 and 3, and the depth of engagement of said teeth with the contact buttons, 5 and 6, can be varied and regulated by longitudinal adjustment of the wheel, 4, with respect to said buttons. Such adjustment is preferably effected by moving the shaft, 7, in one bearing, the bearing provided by the bushing, 13, being somewhat elongated to permit of such adjustment, and the other bearing formed by the bushing, 14, being longitudinally movable by reason of the threaded engagement of said bushing with the boss, 15, of the casing, 1, in which it is mounted. The shaft, 7, is secured against endwise movement in the bearing, 14, by engagement of its shoulder, 16, with the inner end of the bushing, and its applied head, 17, with the shoulder formed by counterboring the outer end of the bushing at 18 to accommodate said head, 17. Anti-friction washers, 19, are inserted to take the thrust at each of these shoulders, and the shaft, 7, is thus rendered positively adjustable in axial direction by adjustment of the bushing, 14. The bushing may be locked at any position of such adjustment by means of a lock nut, 20, impinging upon the boss, 15, of the casing. The driven pinion, 8, is formed with an elongated face sufficient to maintain engagement of its teeth with the gear, 9, throughout the range of adjustment of the shaft, 7.

Preferably the driving train, 11, is mounted as shown at the opposite side of the casing, 1, from the adjustable bearing, 14, so that the adjustment of said bearing, resulting in a variation in the quality of tone produced by the vibrating diaphragms, 2 and 3, may be effected while the toothed wheel, 4, is being rotated by operation of

the crank, 11; that is, operation of the crank does not in any way interfere with the adjustment of the bushing, 14.

By reference to Fig. 2, it will be noted that the contact buttons, 5 and 6, of the diaphragms are so related to the toothed wheel, 4, that when the button, 5, is in engagement with the point of one of the teeth of the wheel, 4, the button, 6, is positioned midway between two of such points, that is, in a depression of the corrugated periphery of the wheel. This permits the two diaphragms to move simultaneously in the same direction and the contact button on the diaphragm to follow the contour of the corrugations remaining substantially continuously in contact therewith over the up-raise and depression. And, assuming that the position of the diaphragm, 3, illustrated in Fig. 2, is substantially its normal position, while the diaphragm, 2, is therein illustrated as yieldingly deflected away from its plane form, it will be seen that this relation of the parts requires less power to be applied to the shaft, 7, for vibrating the diaphragms than if they were simultaneously moved in opposite directions, in which event both diaphragms would be resisting their deflection from normal position at the same time. With the present arrangement, the return of the diaphragm, 3, to normal position will even to some extent assist in the deflection of the other diaphragm away from its normal, if the teeth of the cam wheel, 4, are as shown, inclined at both sides of their points.

It may be understood that, except as to the last mentioned feature, it is not essential that this signal device be made with two diaphragms, but when two diaphragms are employed, the casing may be fitted with two separate horns for discharging the sound emitted from each diaphragm. If it is desired to discharge the sound all in one general direction, these horns may be bent substantially at right angles, as illustrated at 21 and 22 in Fig. 3; while if a general distribution of the sound is desired, the horns may discharge simply in opposite directions as shown at 23 and 24, in Fig. 4. For increasing the convenience of either directing or distributing the sound of the device, the casing, 1, should be swivelly mounted upon a vertical pivotal fixture as, for example, that illustrated in Fig. 5, in which a post member, 25, depending rigidly from the casing, 1, is carried in a socket, 26, formed integrally with a mounting base plate, 27, extending in a plane parallel to the axis of the socket, 26, for attachment to a vertical surface. If the direction of discharge of the sound is fixed during operation of the signal, the socket, 26, may be slotted as at 28, and provided with a clamping screw, 29, for fixing the post, 25, against rotation.

5. In Fig. 1 there is illustrated a mounting

base or pedestal for attaching the signal device to a horizontal surface, the base plate or flange, 30, extending in a plane perpendicular to the axis of the socket, 31. The post, 32, depending from the casing, 1, is formed with a groove in which a ball, 33, may be caused by a set screw, 34, to impinge for fixing the casing, 1, against rotation. A similar swivel connection is shown in Fig. 6, formed in a socket, 35, attached to a stake or post, 36, which may be of any suitable length and adapted to be thrust or driven into the earth by reason of its pointed lower end, 37. For certain purposes, the post or stake may be reduced in dimensions to a mere lag screw, 38, as shown in Fig. 7, secured directly to the casing, 1, and adapted to engage any convenient wooden surface for temporary mounting of the signal.

As this signal is designed primarily for temporary installation with a view to its prompt removal, it is provided with a carrying handle which is preferably cast integral with the casing, 1, as shown at 39 on Fig. 1. But, in operation of the device, the handle has the further function of steadyng the casing while the operating crank, 11, is being turned, particularly where such mounting means are employed as illustrated in Figs. 6 and 7. Especially with the mounting post, 36, shown in Fig. 6, the crank shaft 10, would be at a considerable distance from the ultimate point of support of the device, that is, where the post, 36, enters the ground; but, by steadyng the casing, 1, by grasping the handle, 39, with one hand, while operating the crank, 11, with the other, a very satisfactory action is obtained and simultaneously, if desired, the casing, 1, can be rotated upon its swivel connection with the mounting means, for distributing the sound over a wide area.

I claim:

1. In a signal mechanism comprising a pair of diaphragms, each provided with a contact button, a toothed wheel mounted to rotate between said diaphragms with its corrugations in continuous operative contact with both of said buttons, said parts being disposed for contact of each button with the crest of the projecting tooth of the wheel when the other button is registered with the bottom of a depression in the wheel and for substantial maintenance of contact of the button with the corrugations throughout the upraise and depressions thereof.

2. A signal device comprising a pair of diaphragms disposed in substantially parallel planes, means positioned between said diaphragms adapted to vibrate them simultaneously and separate horns associated with said diaphragms respectively, and each bent substantially at right angles to discharge the vibration from the diaphragms in about the same direction.

3. A mechanical signal device comprising a casing, an operating crank journaled therein, mounting means extending from said casing and a steadyng handle on the casing to coöperate with said mounting means in resisting the reaction of the operating crank.
4. A mechanical signal device comprising a casing, an operating crank journaled therein, a sound discharging horn extending from said casing, mounting means and a swivel connection between the same and said casing disposed to permit pivotal movement of the casing about an axis at right angles to the aforesaid horn, and a steadyng handle on the casing.
5. A mechanical signal device comprising

a casing, an operating crank journaled therein, mounting means and a disengagable swivel connection between said mounting means and the casing together with a steadyng handle on the casing.

6. A mechanical signal device comprising a casing, an operating crank journaled therein, mounting means extending from said casing and comprising a pointed post or stake adapted to be driven into the ground, and a steadyng handle on the casing for resisting the reaction of the operating crank.

In testimony whereof, I have hereunto set my hand at Chicago, Illinois, this 6th day of December, 1918.

JOHN E. GENN.
